UNITED STATES PATENT OFFICE.

EMIL JAGENBERG, OF DUSSELDORF, GERMANY.

LABEL GUMMING AND ATTACHING MACHINE.

1,100,741.

Specification of Letters Patent.

Patented June 23, 1914.

Application filed October 18, 1913. Serial No. 795,834.

To all whom it may concern:

Be it known that I, EMIL JAGENBERG, manufacturer, a subject of the German Emperor, and residing at 107 Himmelgeisterstrasse, Dusseldorf, Germany, have invented certain new and useful Improvements in Label Gumming and Attaching Machines, of which the following is a specification.

The present invention relates to a device 10 for drawing labels from the pile and, after they have been provided with an adhesive, applying them to boxes, bags and the like.

The present invention is characterized in that the slide, which is provided with the adhesive and which draws the label from the pile is moved after seizing the label in a direction vertical to its plane by aid of a rod, so that the label is peeled off it and applied to the box, the paper bag or the like. 20 and pressed thereagainst. This operation has certain advantages, as the adhesive frequently possesses such adhesive power, that the labels will tear when drawn off the slide in the direction of their plane, what will not 25 occur when the labels are peeled off.

In the accompanying drawings the present invention has been exemplified.

Figures 1, 2 and 3 illustrate three different operative positions of the device; Fig. 4 is 30 a cross section on the line A—B in Fig. 2.

By means of the cam drum a which is fitted on a shaft a^1 driven by any suitable means, the slide d is reciprocated in the guide d^1 by aid of a pin b carrying a roller b^1 . 35 This slide d has ears d^2 on which a plate g is pivoted by means of pin f ; to the underside of this plate is fitted a roller h which rides on a rail i . This rail is pivoted on the pin j secured in the body c of the machine and is vertically reciprocated by means of a 40 rod k hinged to its other end by a pin j^1 . This rod k is coupled to the bell crank k^1 , which is rotatably fitted to the body of the machine c on the shaft k^2 and rides with its other end, carrying a roller k^3 on a cam a^2 fitted to shaft a^1 . In consequence of the rotation of the shaft a^1 the bell crank will therefore be swung to and fro whereby the plate i is raised and lowered to a given extent and at given periods.

At a distance above the plate g the adhesive applying rollers m are journaled in the ears of bearings m^1 between which the adhesive tank n is held into which the first roller m dips, so that it takes the adhesive from the tank n . The ears m^1 are rotatably

fitted by means of pin m^2 to standards c^1 fitted to the body of the machine. On the pin m^2 is also fitted a lever m^3 which is coupled by a pin m^5 to a rod m^4 . This rod m^4 is coupled at its other end to a shaft m^6 60 which carries at one end a roller m^7 riding on a cam a^3 and at its other end is secured to a lever m^8 pivoted on pin c^2 to the body c of the machine. The cam a^3 is fitted on the shaft a^1 so that on the latter revolving the lever m^3 and therewith the rollers m are 65 swung to and fro.

When by the rotation of the drum a the slide d with the plate g is advanced, the lower roller m will transfer adhesive to the plate g . The slide d is advanced so far until the plate g is beneath the label box o , which is pivoted with its carrier arm o^1 by means of pin o^2 to the standard c^3 . Against the arm o^1 carrying the label box o bears from below a rod o^3 which is guided in a guide c^6 on the body of the machine. The lower end of this rod bears against the flat end of a lever o^4 , fitted to a shaft o^5 , which is rotatably journaled at c^6 in the body of the machine. To the other end of this shaft is fitted a lever o^6 , the end of which carries a roller o^7 , which rides on a groove o^8 of a cam a^5 . This cam is fitted to a shaft a^1 . In 70 consequence of this arrangement the label box o is raised and lowered when the shaft a^1 is revolved. The slide then remains stationary and the label box o settles down on the plate g which has received the adhesive 75 (Fig. 2), and the lowermost label will stick to this plate when the label box rises again. Now the slide d together with plate g is further advanced by the cam drum a until the lower fixed jaw p^1 of a gripper enters 80 into a slot r in the plate g . The front edge of the label enters between the jaws of the gripper, the upper jaw p^2 of which, pivoted to the plate c^4 secured to the body of the machine is lowered by means of a lever s 85 attached to it, and coupled by means of a rod s^1 to a bell crank s^2 pivoted on the body of the machine. This bell crank s^2 is coupled to a rod s^3 , which has at its free end a fork s^4 and a roller s^5 , which rides on a cam a^4 90 fitted to shaft a^1 .

At the same time the roller h passes under a hook t secured to the rail i , which hook takes the plate g down with it, when the rail i is drawn down by the rod k , so 100 that the label held back by the gripper is drawn off upward, or so to say, peeled off.

(Fig. 3). When now the slide d recedes together with plate g , the label which has received the adhesive on its underside hangs from the gripper. When the slide d with the plate g recedes, the rail i is again raised by means of the rod k and at the same time the ears m^1 with the adhesive rollers m and the tank n rise, so that the receding plate g will not come into contact with the lower roller m and be soiled by it with adhesive.

To the bottom of the machine body is fitted a shaft like guide u in which a slide u^1 moves up and down. This slide has at its top a plate or platform u^2 and in its middle wall u^3 a slot u^4 , through which the shaft a^1 projects. At the lower end the slide is linked by means of a link member u^5 to a bell crank u^6 , which is pivoted on a pin c^7 in the body of the machine. The other arm 20 of the bell crank is coupled to a rod u^7 , the free end of which bears a fork u^8 , which engages around the shaft a^1 . To this fork is fitted a roller u^9 , which is pressed by the weight of the slide u^1 against a cam a^6 fitted to shaft a^1 . By the rotation of the shaft a^1 thus the slide is raised and lowered in the desired manner. Beneath the machine top a belt conveyer v is carried over the roller v^1 journaled in the body c . The 30 other end of the belt and the other roller over which it is conducted are not shown in the drawing. This belt is moved by the roller v^1 being suitably driven, and travels in the direction shown by the arrows. The packages bags, boxes and the like, which are to be labeled, are placed on this belt v , and are thereby fed to the shaft u . In the side of the latter is an opening u^{10} through which the packages, bags, boxes and the like can enter into the shaft u , when the slide u^1 is in its lowermost position. When this slide is, however, in a higher position, its one side wall will prevent the packages or the like from passing through the 45 opening u^{10} . The belt v advances at a uniform speed, so that it will slip beneath the packages when these are retained by the slide. When the slide is thus in its lowermost position, a package w will be advanced by the belt v on to the platform u^2 through the opening u^{10} , so that when the slide moves upward it will force it out through the top of the shaft. This upward stroke of the slide u^1 with the package on

it occurs at the moment when the slide d 55 with the plate g recedes. The package therefore rises from below against the label held by the gripper. The slide u^1 with the package w and the label then further rises and forces the package into a shaft x attached 60 to the body of the machine. This shaft has such a section that the packages or bags can be pressed tightly only into it. Thereby the projecting edges of the label are folded over the sides of the package and the latter 65 is pressed against the lowermost package in shaft x whereby the label is pressed down on it. All packages contained in shaft x are simultaneously pressed upward and the uppermost package is pressed out and falls 70 on an incline (not shown). The packages are held by their friction against the walls of the shaft against their falling out. The slide u^1 may therefore recede so as to allow of a fresh package w being pushed onto it. 75 Then the slide d again advances and a new operation is commenced.

I claim:

1. A label gumming and attaching machine comprising a slide, a plate pivoted thereto, a gumming roller adapted to engage the plate, means for tilting the plate, a label magazine adapted to be lowered upon the plate to deposit the lowermost label thereon, means for drawing said lowermost 85 label off said plate, and means for carrying a box into contact with said label.

2. A label gumming and attaching machine comprising a slide, a plate pivoted thereto, a roller carried by the plate, a tilt- 90 able rail engaged by the roller, means for tilting said rail to thereby tilt the plate, a pivoted gumming roller adapted to engage the plate, a pivoted label magazine adapted to be lowered upon the plate to deposit the 95 lowermost label thereon, means for drawing said lowermost label off said plate, a shaft, and a platform vertically movable in said shaft, which platform is adapted to support a box and carry the same into contact with said label.

In testimony whereof I have hereunto set my signature in the presence of two witnesses.

EMIL JAGENBERG.
